UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

SHOE-SEWING MACHINE.

1,231,868.

Specification of Letters Patent.

Patented July 3, 1917.

Original application filed July 27, 1911, Serial No. 640,836. Divided and this application filed May 21, 1913. Serial No. 763,909.

To all whom it may concern:

Be it known that I, ANDREW EPPLER, a citizen of the United States, residing at Lynn, in the county of Essex and Commonwealth of Massachusetts, have invented certain Improvements in Shoe-Sewing Machines, of which the following description, in connection with the accompanying drawings, is a specification, like reference characters on the drawings indicating like parts in the several figures:

The invention relates to shoe sewing machines and more particularly to devices for severing the thread at the completion of the sewing operation and for holding it at the beginning of the succeeding sewing operation.

This application is a division of application No. 640,836, filed July 27, 1911.

The object of the invention is to provide novel and improved devices for severing and holding the thread by which the thread may be severed at the completion of the sewing and its free end held under proper tension during the formation of the first stitch at the beginning of the succeeding operation.

To this end the invention contemplates the provision, in a sewing machine having a hooked needle and a looper, of a thread severing device and a thread holding device which holds the severed end of the thread under tension during the formation of the first stitch while giving up thread to the thread handling devices. With this construction of thread holding devices the severed or free end of the thread is properly held to insure the formation of a tight stitch at the beginning of the seam, without danger of breakage due to sudden strains or

pulls put upon the thread by the rapidly moving thread handling devices, since the thread holder will give up thread to cushion or relieve any strain in excess of the tension requisite for the formation of a tight stitch.

The thread holding devices may be of any suitable construction which will secure the results referred to, but, owing to the simplicity of the construction, it is preferred to employ a holder which frictionally holds the thread so that it may slip and to so arrange the cutter that a free length of thread is left beyond the holder equal to or greater than that which will be drawn through the

holder during the first cycle of the stitch-forming devices at the beginning of the 55 sewing.

The invention also contemplates the provision of a novel and improved thread finger which insures its proper operation on the thread at the beginning of the sewing.

The features of the invention will be readily understood from an inspection of the accompanying drawings and the following detailed description of the apparatus illustrated therein.

In the drawings Figure 1 is a side elevation of so much of a welt and turn sewing machine as is necessary to illustrate the application of the present invention thereto; Fig. 2 is a detailed front elevation showing 70 the looper thread finger and thread cutting and holding devices; and Fig. 3 is a detailed sectional view on line 3—3 Fig. 2.

In the drawings the invention is shown as embodied in the welt and turn sewing machine shown and described in my prior application, Serial No. 447,542, filed August 8, 1908. This machine is provided with a curved hook needle 1, a looper, a thread finger 3, a feed point 4, a channel guide 5, 80 a welt guide 6 and a back gage 7, which are operated in a well known manner to unite the insole and upper or the insole, upper and welt by a chain-stitch seam. The machine is also provided with devices indicated at 8 for 85 severing and holding the welt at the completion of the sewing in case the machine is being used upon welt shoes.

The devices for severing and holding the thread at the completion of the sewing, in 90 the construction shown, consist of a spring clamping plate 9 and a thread severing knife 10 which projects from the plate. The clamping plate is adjustably secured to the looper 2 by a screw 11 and co-operates with 95 the surface of the looper in clamping the thread as indicated in Figs. 2 and 3. The clamping plate is so adjusted that the thread is held frictionally between it and the looper with sufficient force to insure the proper tension upon the thread and at the same time to allow the thread to slip forward toward the thread handling devices during the action of these devices in forming the first stitch. The knife 10 is so arranged with relation to the gripping surfaces of the plate 100 105

9 and looper that a considerable length of free thread is provided beyond the thread holder.

After the machine has been stopped at the completion of the sewing and after the welt has been severed, in case the machine is operating upon welt shoes, the shoe is manipulated by the operator to carry the thread between the clamping plate 9 and the surface of the looper and then by a downward movement of the shoe the thread is carried across the edge of the knife 10 and severed.

When the machine is started at the beginning of the next sewing operation, the severed end of the thread is held beyond the thread handling devices by the thread holder and resists any forward pull on the thread with sufficient force to insure the formation of a tight initial stitch. During the formation of the stitch, however, the thread may slip forward through the thread holder and is still held under tension owing to the length of free thread beyond the holder, this length of thread being such that the thread will not be pulled out of the thread holder by the stitch-forming devices. As the sewing progresses, the feed of the shoe will draw the thread out of the thread holder.

When the machine is in proper position for the removal of the shoe the thread finger 3 is in substantially the position indicated in Figs. 2 and 3, and the thread is liable to pass up the shank of the thread finger when it is carried up into the thread holder devices by the operator. If this should occur the thread finger would not operate properly upon the thread in forming the first stitch. In order to insure the proper engagement of the thread finger with the thread, the finger is provided with the spur or projection 12 under which the thread passes and which operates to retain the

thread in proper position with relation to the thread finger and insures the proper action of the thread handling devices when the machine is started.

While it is preferred to employ the specific construction and arrangement of parts shown and described, it should be understood that this construction and arrangement is not essential to the broader features of the invention and may be varied or modified without departing therefrom.

Having explained the nature and object of the invention, and specifically described one form of mechanism in which it may be embodied, what I claim is:—

1. A shoe sewing machine, having, in combination, a stitch forming mechanism including a looper and a thread finger, a thread holding device for holding the free end of the thread and a spur on the thread finger under which the thread leads to the holding device. 60

2. A shoe sewing machine, having, in combination, stitch forming devices including a hooked needle and a looper, a clamping plate secured to the looper and coöperating with the surface of the looper to frictionally hold the thread passed between it and the looper by the operator, and a knife blade projecting from the front of the plate. 70

3. A shoe sewing machine, having, in combination, stitch forming devices including a hooked needle and a looper, a clamping plate 75 extending along the surface of the looper, and a blade 10 projecting from the front of the plate.

In testimony whereof, I have signed my name to this specification in the presence of two subscribing witnesses.

ANDREW EPPLER.
